(57) **CLAIM**

We claim the ornamental design for a biochip, as shown and described.

DESCRIPTION

FIG. 1 is a front view of a biochip showing our new design.

FIG. 2 is a rear view thereof.

FIG. 3 is a left view thereof.

FIG. 4 is a right view thereof.

FIG. 5 is a top view thereof.

FIG. 6 is a bottom view thereof.

FIG. 7 is a bottom front left isometric view thereof; and,

FIG. 8 is a top rear left isometric view thereof.

The broken lines depict portions of the biochip that form no part of the claimed design.
